UNITED STATES PATENT OFFICE.

WEBSTER E. JANSSEN, OF NEW YORK, N. Y.

DESIGN FOR A COMBINED PLAYER PIANO AND WRITING DESK.

Application filed September 21, 1928. Serial No. 28,229. Term of patent 14 years.

To all whom it may concern:

Be it known that I, WEBSTER E. JANSSEN, a citizen of the United States, residing in the borough of Manhattan, in the city and county of New York and State of New York, have invented a new, original and ornamental Design for a Combined Player Piano and Writing Desk, of which the following is a specification, reference being had to the accompanying drawing, forming a part thereof.

The figure is a perspective view of a combined player piano and writing desk showing my new design.

I claim:

The ornamental design for a combined player piano and writing desk as shown.

WEBSTER E. JANSSEN.
